(57) **CLAIM**

The ornamental design for an electric lift transfer chair, as shown and described.

DESCRIPTION

FIG. 1 is a front perspective view of an electric lift transfer chair, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof, shown in an alternate position of use.

The broken lines in the drawings illustrate the portions of the electric lift transfer chair, which form no part of the claimed design.

1 Claim, 9 Drawing Sheets
